UNITED STATES PATENT OFFICE.

OSBORN P. LOOMIS, OF SOMERVILLE, MASSACHUSETTS, ASSIGNOR TO THE
LOOMIS ELECTRIC MANUFACTURING COMPANY, OF NEW YORK, N. Y.

ELECTRIC SWITCH.

SPECIFICATION forming part of Letters Patent No. 431,118, dated July 1, 1890.

Application filed September 3, 1888. Serial No. 284,399. (No model.)

To all whom it may concern:

Be it known that I, OSBORN P. LOOMIS, a citizen of the United States, residing at Somerville, in the county of Middlesex and State 5 of Massachusetts, have invented certain new and useful Improvements in Electric Switches, of which the following is such a full, clear, and exact description as will enable any one skilled in the art to which it appertains to 10 make and use the same, reference being had to the accompanying drawings, forming part of this specification.

My invention relates to an electric switch having as a bridging means a pair of oppositely-arranged terminals, which engage with a spring-pressure the bridging-contact, which consists in a member with spring ends adapted to engage the respective terminals with a spring-pressure, said contacting parts there- 15 by exerting reciprocal spring-pressures; and, further, the invention relates to the peculiar manner of operating the pivoted switch-arm, partly through means of the handle and partly through means of a spring, and also 20 in the novel arrangement of said spring, which exerts its force on a dead-center when the pivoted switch-arm is in full closed position on the terminals, and serves to quickly force the switch open after the opening move- 25 ment thereof has almost been completed through the manipulation of the handle.

The invention further relates to the novel and peculiar arrangements and constructions of the several detail parts of the switch, all 30 as hereinafter fully described and claimed.

The advantages peculiar to my improved switch are that firm and reliable connection is secured between the terminals and the bridging-contacts by virtue of a reciprocal 35 spring-pressure exerted therebetween, the contacting surfaces are always kept clean and bright, and both sides or poles of the circuit may be simultaneously opened and closed, and that the opening of the switch is not de- 40 pendent upon the manipulation of the handle after the initial movement has been given the same.

I have illustrated in the accompanying drawings, in which like numbers of reference 45 50 designate like and corresponding parts

throughout, a double-pole electric switch constructed after the manner of my invention.

Figure 1 is a plan view of the switch in open position and with the inclosing-casing removed, the view being partly in section on a plane indicated by line 1 1, Fig. 2. Fig. 2 is a view similar to that in Fig. 1, but with the switch in closed position. Fig. 3 is a view of the switch, together with its casing, in section on a plane indicated by line 3 3, Fig. 1, 55 the line-terminals being omitted in this view. Fig. 4 is a partial side view of the right-hand side of Fig. 2.

Referring to the drawings, 6 designates a circular switch base or board, which may be made 60 of wood or any other suitable insulating material, and in a flat form, so that it may be conveniently attached to a plane surface. At the center of the base 6 is a pivot pin or post 7, provided with head 8 and secured in fixed 65 position by means of suitable nuts and washers, though any other means of sustaining the post may be used. The switch-arm 9, preferably made of hard rubber, though any suitable insulating material will answer, is 70 formed with a central eye, by means of which it is journaled on post 7, so as to be movable in either direction thereon.

At each end of the switch-arm 9 is attached a bridging-contact 10, consisting in a metal 75 plate or strip bent substantially U-shaped and having resilient ends. These contacts embrace in reverse manners the respective ends of the switch-arm, to which they are attached by means of screws 11, which are set 80 through the arch of the U shape to allow the spring ends of the contacts to project free and to opposite sides of the switch-arm. The ends of these contacts look in opposite directions relatively to the length of the arm, which 85 is limited in one direction of its movement on its pivot by the stop 12, fixed in the base. A suitable washer-plate 33 is interposed between the arm and the base 6, so as to permit the flaring ends of the contacts 10 to clear the 90 base as its arm moves on its pivot.

Correspondingly situated relatively to the pivotal point of the switch-arm are the pairs of metallic line-terminals 13 and 14, respectively, which are located in opposite sides or 95 100

portions 15 and 16 of an electric circuit. These terminals 13 and 14 are arranged oppositely, so as to constitute practically a fork or clamp-like device, which is capable of exerting a spring-pressure upon a member entered therein by virtue of the resiliency of the terminal 14, which is formed with a split end to compensate for any unevenness that may be in the surfaces of the contacts. These terminals 14 are secured in position substantially parallel to the base upon the brackets 17 17, with which they are electrically connected. The brackets 17 are fastened to the switch-base by screws 18 18, and are each provided with a binding-screw 19, the ends of which engage the lines in the sockets 20, which are formed suitably in the base 6, and for the purposes of the invention the brackets and terminals 14 may be one piece. The terminals 13, over which the terminals 14 project, are secured to the switch-base by screws 21, and are both provided with a binding-screw 22, which serves to bind the lines 15 16 in the respective sockets 20. Thus when each pair of terminals 13 and 14 are bridged across the circuit 15 16 will be closed in the manner that is obvious.

The terminals 13 and 14 are simultaneously bridged over by the bridging-contacts 10 10 being pushed, with their closed or arched parts foremost, in between the terminals when the switch-arm is turned in the direction of the movements of the hands of a clock. The free ends of the spring-terminals 14 are slightly upturned to afford easy entrance of the bridging-contacts. It will be evident that when the contacts are entered between the terminals there will be a reciprocal spring-pressure exerted between such parts, by reason of the resiliency of the terminals 14, and of the ends of the bridging-contacts 10. The constant rubbing of these parts against each other, in operating the switch, will keep the metallic surfaces bright and clean, and thereby afford good electrical connection, which will be rendered all the more reliable and close because of the mutual pressure between the terminals and contacts. The bridging-contacts of the switch-arm are preferably located equal distances from the pivotal point thereof, and the coacting line-terminals are situated correspondingly in the path moved over by such contacts, and with the free ends of the terminals 14 extending in opposite directions.

The switch-arm is shifted back and forth on its pivot by the handle 23, the cross-head of which is made of suitable insulating material, such as ebonite. The shank of the handle is formed with an axial socket 24, and the foot 25 of the handle is broadened out into a rectangular-shaped body, which is formed with the curved slots 26 26, of equal curvatures struck from the axis of the handle as a center. The socket 24 of the handle receives the fixed stem 27, which projects from the yoke 28 in axial alignment with the axis of the pivot of the switch-arm. This yoke-

piece 28 connects the pins 29 29, which are fixed at equal distances from the center of the switch-arm and extend parallel with the axis of such pivot, and the heads of which are received by the slots 26 26, respectively, which are arranged diametrically opposite. One of the pins 29 is engaged by the free end of the spring 30, which has its other end coiled about the bar 31, which is fixed in the switch-base. This spring is arranged, as will be clearly understood from Figs. 1 and 2, so as to exert its force on the switch-arm 9 in a way that tends to turn it on its pivot in the direction opposite to that in which the hands of a clock move, except when the switch-arm is in full closed position, as shown in Fig. 2. In this latter position of the switch-arm the force of the spring 30 will be directed along the line of length of the arm, and consequently on a dead-center, thereby in no wise tending to shift the switch-arm when the latter is closed. Obviously the movement of the switch-arm into the closed position tends to wind the spiral of the spring and to make it tense, so as to store up power by which the switch-arm may be quickly opened after being moved off the dead-center, as before described. As soon, however, as the switch-arm is started to be opened and has moved nearly off the terminals the full force of the spring will be exerted thereupon in such a way as to quickly shift the arm back against the stop 12 into open position. The spring-pressure between the bridging-contacts and the terminals will of course tend to clamp the switch-arm in confinement; but the power of the spring 30 will overcome this as soon as the dead-center is passed. It will be noted that the contacts 10 and terminals 13 14 are designed to make quite an extended contact, and that it is not until the contacts are about to move off the terminals that the spring 30 comes into play.

When in opening the switch from the position shown in Fig. 2 the handle 23 is grasped and slightly turned, the switch-arm is likewise moved, since the pins 29 are then at the ends of the slots 26, as shown in Fig. 1. The spring 30 now comes into play and tends to force the switch-arm open independently of the handle, which it succeeds in doing when it overcomes the grip between the spring-terminals and bridging-contacts. Under the action of the spring the switch-arm will be snapped open with a quick movement, in which the pins 29 are moved entirely through the slots 26 in the handle from the position shown in Fig. 1 to that shown in Fig. 2. Thus both sides of the circuit are opened simultaneously by the automatic action of the switch-arm, after the handle has been given the initial movement by the operator, so that the sudden and simultaneous breaking of the circuit at each side thereof is insured and is wholly independent of the slow movement of the handle by the operator, the switch being out of control of the operator after he gives the handle a partial turn. The simultaneous

closing of both sides or poles of the circuit and the simultaneous and sharp quick opening thereof are desirable qualities in an electric switch, and especially so when used with a high-potential current, where, on account of the sluggish movements of the switch-arm, the non-simultaneous contact between the terminals and the bridging-contacts would cause sparking, which would soon burn out the contacts and impair the switch.

The operative parts of the switch are inclosed by the circular cup-shaped metal casting 32, which is suitably fitted over the switch-base 6, and is provided with a central opening for the handle 23 to pass through.

As the detail parts of the improved switch will admit of modifications, I wish to be understood as not confining myself to the exact arrangement and constructions herein shown.

Having thus described my improvements in electric switches, what I claim as my invention, and desire to secure by Letters Patent, is—

1. In an electric switch, the combination, with the pivoted switch-arm 9, carrying the contacts and provided with a pin, such as the pin 29, the terminals engaged by said contacts, of the coil-spring 30, made fast by one end and having the other end bent to engage the said pin on the switch-arm, the movement of which latter in one direction tends to wind the spring and make it tense, the said spring

exerting its pressure upon the side of the pin remote from the pivotal center of the arm when the latter is in closed position, substantially as and for the purpose set forth. 35

2. In an electric switch, the combination, with the switch-base 6, the switch-arm 9, made of suitable insulating material and pivoted intermediate its ends, and provided with the spring bridging-contacts 10 10, the line-terminals 13 14, arranged oppositely and in correspondingly-located pairs and adapted to receive the bridging-contacts 10, the spring 30, made fast by one end and connected by the other end to the switch-arm, the movement of which latter in one direction tends to wind the spring and make it tense, the pins 29, fixed to the switch-arm, and the yoke 28, connecting them, the stem 27, projecting from the yoke in axial alignment with the axis of the pivot of the switch-arm, the key 23, formed with the socket 24 and having the foot 25, formed with the curved slots 26 26, all substantially as and for the purpose set forth. 55

In testimony whereof I have hereunto set my hand and seal, this 20th day of August, 1888, in the presence of the two subscribing witnesses.
